UNITED STATES PATENT OFFICE.

THOMAS M. HOUSE, OF RICHMOND, VIRGINIA.

ADJUSTABLE SWINGING WINDOW-SASH.

1,105,199.

Specification of Letters Patent. Patented July 28, 1914.

Application filed April 5, 1912, Serial No. 688,750. Renewed March 12, 1914. Serial No. 824,315.

To all whom it may concern:

Be it known that I, THOMAS M. HOUSE, a citizen of the United States, residing at Richmond, in the county of Henrico and State of Virginia, have invented certain new and useful Improvements in Adjustable Swinging Window-Sashes, of which the following is a specification, reference being had to the accompanying drawings.

10 This invention relates to improvements in windows and has for its object to provide a window embodying vertically movable sashes mounted in the window frame for swinging movement, and means for securing 15 said sashes in their open position at any point in the frame.

Another object of the invention is to provide swinging window sashes having stiles and supplemental stiles pivotally connected 20 at their lower ends, and means for mounting said supplemental stiles whereby a practically air tight joint is formed between the same and the stiles of the sashes when said sashes are closed.

25 Another and more specific object of the invention resides in the provision of vertically sliding supplemental stiles mounted in the window frame and the sashes pivotally mounted upon the lower ends of said stiles, 30 said sashes having swinging movement through an arc of substantially ninety degrees, and means carried by the sashes co-operating with means mounted upon the supplemental stiles to engage the window 35 frame and securely hold the stiles against further sliding movement.

Another object of the invention is to provide a device of the above character which consists of comparatively few elements which 40 may be manufactured and installed at a comparatively small cost and produce a device which is reliable in operation.

With the above and other objects in view, the invention consists in certain constructions, combinations and arrangements of the parts that I shall hereinafter more fully describe and claim.

For a full understanding of the invention reference is to be had to the following description and accompanying drawings in which—

Figure 1 is a front elevation of a window partly in section constructed in accordance with the present invention; Fig. 2 is a horizontal section taken on the line 2—2 of Fig.

1; Fig. 3 is a perspective view showing one of the sashes in its open position; Fig. 4 is a section taken on the line 4—4 of Fig. 1; Fig. 5 is an enlarged section illustrating the sash lock in detail; Fig. 6 is a detail fragmentary perspective view of the supplemental stile; Fig. 7 is a perspective view of the plate secured to the window stile which carries the stop lug; and Fig. 8 is a detail section of the supplemental stile illustrating on an enlarged scale the form of guide eyelet for the sash cord which is carried by said stile.

Corresponding and like parts are referred to in the following description and designated in all the views of the accompanying drawings by the same reference numerals.

Referring in detail to the drawings 5 designates generally the window frame which is of the usual construction and is 75 provided with the weight chambers 6 separated by the vertical partition member 7. The inner wall 8 of the window frame at each side thereof is mortised as at 9 to receive a parting bead 10 which separates the 80 two sashes of the window for vertical movement in spaced grooves or channels. The rear wall 11 of the frame is extended inwardly beyond the side wall 8 thereof and forms a stop for one of the sashes, a stop strip 12 being secured to the inner wall of the frame adjacent to its inner edge to provide a stop or holding strip for the other of the window sashes. As the manner of 85 mounting the two sashes in the window 90 frame is identical the detailed description of one of such mountings will suffice for both of the sashes.

In the sash receiving grooves of the window frame the supplemental stiles indicated 95 generally by the numeral 13 are slidably mounted. These supplemental stiles differ slightly in proportion for the upper and lower sashes but are each of channel form in cross section, as clearly shown in Fig. 2. The edge of one of the side walls of the stile is outwardly flanged as indicated at 14 and loosely fits into a longitudinal kerf 15 formed in the bead 10 and the outer wall 11 respectively of the frame. This flanged wall 100 of the supplemental stile is also provided with an extension 16 which projects laterally from the face of the intermediate portion of the stile and extends the entire length thereof. The window sash 17 has a plate 18 105

110

countersunk in the face of the sash stile and securely fixed thereto by means of suitable screws. The body wall of the supplemental stile 13 is provided at its lower end with an opening to receive a pivot screw 19 which extends through a coinciding opening in the plate 18 and is threaded through the sash stile and into the lower cross bar or rail of the window sash. The plate 18 is provided with a laterally extending stop lug 20 which is cut out of said plate and is disposed for movement in an arcuate slot 21 formed in the lower end of the supplemental stile 13. This lug engaging the opposite end walls of said slot limits the swinging movement of the window sash upon the lower end of the supplemental stile so that the sash is movable from a vertical to a horizontal position or through an arc of substantially 20 ninety degrees.

The window sash is normally held in its closed position by means of the usual counter-balancing weight 22 which is secured to one end of the sash cord 23, said cord passing over the usual guide pulley or sheave (not shown) at the top of the window frame, and then extending downwardly between the parallel walls of the supplemental stile 13. This sash cord extends through a 25 guide eye 24 secured in an opening provided in the body wall of the stile 13 and is suitably fixed to the sash stile as shown at 25. It will be observed that the guide eye 24 is provided with a rounding convex projecting portion which extends outwardly into the channel of the stile 13, thereby providing a smooth surface over which the sash cord moves and eliminates all liability of said cord being cut in the swinging movement of 30 the sash. The secured edge of the guide eye is disposed in a counter-sink or recess provided in the outer face of the supplemental stile 13.

In order to hold the supplemental stile 13 against further vertical movement after the window sash has been moved in the frame in position to be opened or swung out of the frame in order to secure the desired amount of ventilation, I employ the stop device 45 shown in Fig. 4 which consists of a spring plate 26 rigidly fixed at one of its ends to one of the parallel walls of the supplemental stile 13. This spring plate extends from its fixed end in spaced relation to the front wall 50 of the channeled stile 13 and at its other end is angularly extended inwardly as at 27, the extremity of said plate being downwardly flanged as at 28 and disposed in the path of movement of the stop lug 20 carried by the 55 window sash. When the sash is in its normal position, or entirely closed within the window frame, this lug engaging the depending flange 28 of the plate 26 forces said plate inwardly to dispose the holding block 60 29 out of engagement with the frame of the

window. This sash holding block is movable through a rectangular opening 30 in the front wall of the stile 13 and is provided with a serrated or roughened face 29' for gripping engagement with the stop strip 70 12 or the bead 10, as the case may be. By means of this construction it will be readily seen that as soon as the sash has been moved to the desired position in the window frame and said sash swung out of said frame to its open position, the stop lug 20 is disengaged 75 from the lower end of the spring plate 26, thereby permitting said plate to assume its normal condition and project the stop block 29 through the opening 30 of the stile 13 and into engagement with the window frame, thereby holding the stile 13 against further sliding movement and supporting the sash in the position to which it has been adjusted 80 in the frame of the window.

In addition to the foregoing features of construction, I also provide a holding device which is mounted upon the upper end of the supplemental stile 13 whereby the sash may be securely held in its closed position in the frame of the window. This sash lock includes a spring plate 32 fixed at one end to the body wall of the supplemental stile and provided at its other end with a cylindrical conical shaped stud 33 which is loosely disposed through an opening in the stile and is adapted to be received in a central opening 35 provided in the plate 34 which is fixed to the stile of the window sash. The plate 32 has an opening 36 therein adjacent 90 to its fixed end through which a bolt 37 mounted in the stile 13 is loosely disposed. A nut 38 is threaded upon the end of this bolt and provides means for adjusting the tension of the spring plate 32. When the window sash is swung upwardly and inwardly to its closed position within the frame, it will be apparent that the engagement of the plate 34 with the projecting end of the conical stud 33 will force said stud through the openings in the supplemental stile, and place the spring plate 32 under tension. Thus, when the sash is entirely disposed within the window frame and the stud 33 is opposite the opening 35 of the plate 34, 95 the spring plate 32 in assuming its normal position projects the stud 33 into said opening whereby the window sash is securely held in the frame against casual swinging movement.

As before stated, the channeled stile 13 is provided with a flange 14 for engagement in a groove of the window frame and for the purpose of effecting an air tight joint between the sash and the window frame when the sash is closed, I provide the edge of the side stile of the sash upon its outer face with a recess 39 to receive the projecting portion 16 of the side wall of the supplemental stile 13, and in the base of this recess a strip of 1

felt, rubber, or other compressible material indicated at 40 is secured in any preferred manner. This strip of material when the sash is swung to its closed position, engages 5 upon the surface of the projecting portion 16 of the sliding stile and effectually prevents the flow of air between the fixed window stile and the supplemental stile. The flange 14 of the sliding stile serves to prevent 10 the exterior cold air finding its way between said stile and the frame of the window and into the room or apartment.

From the foregoing description taken in connection with the accompanying drawings, it is believed that the construction and manner of operation of my improved window will be clearly understood.

By the provision of my improved holding device for the supplemental stile whereby 20 the stile is securely held in position in the swinging movement of the window sash, the sash is at all times maintained in its proper position with relation to the frame when it is opened and closed, and the liability of the 25 sash assuming an angular position in the frame owing to a greater weight at one side of the sash than at the other is entirely overcome. Thus, the sash is prevented from binding at its sides against the frame of the 30 window and the supplemental stiles are also relieved of the pressure of the sash which would result from such an unequal distribution of the weight.

As the device as a whole comprises but 35 few elements in its construction, it will be obvious that the same can be produced at small cost and easily and quickly installed in position for use.

While I have shown and described the 40 preferred form and arrangement of the various parts, it will be understood that the invention is susceptible of considerable modification without departing from the essen-

tial features or sacrificing any of the advantages thereof. 45

Having thus described the invention, I claim:

1. The combination with the window frame and a sash mounted therein for sliding and swinging movement, of a spring 50 pressed locking device arranged adjacent to the pivot of the sash, and means carried by the sash to hold the locking device in an ineffective position during the sliding movement of the sash, and adapted to release said 55 locking device for frictional engagement with the window frame at any point in the sliding movement of the sash when said sash is swung out of the frame to its open position to hold said sash against further 60 sliding movement in either direction.

2. The combination with the window frame and sliding stiles mounted therein, a sash pivotally mounted upon said stiles, of leaf springs fixed to the sliding stiles and 65 provided with holding blocks to frictionally engage the window frame, the free ends of said springs being disposed adjacent to the pivots of the sash, lugs carried by the sash to engage said springs and hold the blocks 70 out of frictional engagement with the window frame during the sliding movement of the sash, said lugs when the sash is swung out of the frame releasing the springs to permit the blocks carried thereby to be 75 forced into frictional engagement with the window frame and hold the stiles against sliding movement in either direction when the sash is in its open position.

In testimony whereof I hereunto affix my 80 signature in the presence of two witnesses.

THOMAS M. HOUSE.
